CONNECTER PLUG

Hershel Wayne Chaplin, Morgantown, W. Va., assignor of one-fourth to S. A. Phillips, and fifteen percent to Richard Earle Davis, both of Morgantown, W. Va.

Application August 7, 1934, Serial No. 738,862

3 Claims. (Cl. 173—343)

My invention relates generally to electrical cable or cord connectors, and particularly to connectors of the plug type, and an important object of the invention is to provide a plug connector of the type indicated wherein the receptacle portion and the plug portion can be more easily and quickly separated, notwithstanding the fact that they are in adequately connected condition in ordinary circumstances.

Another important object of my invention is to provide a simplified and efficient plug connector of the character indicated above which is capable of being made at low cost.

Other objects and advantages of my invention will be apparent from a reading of the following description in connection with the drawing wherein for purposes of illustration I have shown a preferred embodiment of my invention.

In the drawing:—

Figure 1 is a side elevational view of the connector plug.

Figure 2 is a transverse vertical sectional view through Figure 1.

Figure 3 is a side elevational view of the plug portion.

Figure 4 is a bottom plan view of the releasing collar on the plug portion.

Referring in detail to the drawing, the numeral 5 refers generally to the plug connector which is composed of the female receptacle portion 6 and the male plug portion 7.

The female receptacle portion 6 is formed of a generally cylindrical dielectric body 8 which has on its lower end a threaded ferrule 9 adapted to be screwed into an outlet, such as a base outlet or socket receptacle and has on its upper end a portion 10 of relatively greater diameter whose upper part is beveled as indicated at 11. The upper part of the body 8 has therein a frusto-conical recess 12 which opens into the top of a cylindrical recess 13.

In the cylindrical recess 13 is arranged an annular contact member 14 which is slightly smaller in diameter than the diameter of the recess 13 and has on its lower end the flange 15 which engages the top of a helical spring 16 lying on the bottom of the recess 13 in such a way as to normally force the contact member 14 upwardly to engage its cupped upper part 17. A conductor 18 connects the contact 14 with the threaded ferrule or shell 9.

An inverted frusto-conical insulator cup 19 is arranged concentrically spaced within the annular contact member 14 within the recess 13, the insulator cup 19 having its lower end de-

pressed below the floor of the recess 13 as shown in Figure 2. A bushing 20 has its upper end abutting the lower end of the insulator cup 19 and has its lower end arranged flush with the lower end of the body 8 and engaging the upper surface of a dielectric plate 21. A riveted conductor 22 passes through the lower end of the insulator cup 19, through the bushing 20 and through the head 23 on the plate 21, and the pin is riveted within the insulator cup 19 and against the lower side of the head on the plate 21. The riveted portion of the pin within the insulator cup 19 constitutes a contact to be engaged by a contact member on the plug portion of the plug connector, while the riveted portion on the lower end of the pin engaging the head of the plate 21 forms the contact for engaging the contact in the receptacle or socket to which the plug connector may be connected.

The plug portion 7 comprises the dielectric 20 solid body 25 which is generally cylindrical in form and has a frusto-conical lower part 26 which is adapted to seat in the frusto-conical recess 12 of the receptacle portion when the plug portion and the receptacle portion are assembled as shown in Figure 2. The upper end of the frusto-conical portion 26 is beveled as indicated at 27 to provide a surface for spreading latches to be described. At three equally circumferentially spaced places the body 25 has 25 above the beveled portion 27 radially inwardly extended notches 28 in each of which is arranged in a chordal direction a part of a pivot ring 29 on which is hinged a latch 30, the ring 29 encircling the body 25.

Each latch comprises the long arm 31 provided at its radially outward end with the right angular hook 32 and hinged at its inward extremity on the ring 29. On the upper side of the portion of the arm 31 adjacent the ring 29 but at a position 40 slightly radially outwardly thereof is the foot 33. When the plug portion is connected to the receptacle portion as shown in Figure 2, the lower side of the latch 30 will rest upon the extreme upper edge of the beveled portion 27 and on the 45 beveled portion 11 of the body 25, in which position the hook 32 engages under the lower edge 34 of the beveled portion 11 on the receptacle body 8.

Telescoped on and concentrically spaced from 50 the cylindrical upper part of the body 25 is the releasing collar 35 which has a depending skirt portion 36 which is provided at the three circumferentially spaced intervals with openings 37 through which the latches 30 are arranged as 55

indicated in Figure 2 and in Figure 1. The portion of the skirt above each opening 37 is inferiorly rounded as indicated at 38 to cooperate with the angulated outer end portion of the foot 33 and also the upper side of the long arm 31 of the respective latch on which the skirt rests in the assembled condition of the connector.

The collar 35 has an interior flange 39 concentrically spaced from the body 25 and against the upper side of which works the lower end of a helical spring 40 whose upper end is confined by a flange 41 on a cap 42, whereby the releasing collar 35 is normally pressed in a downward direction. The effect of the downward position of the collar 35 is to push the skirt down on the upper side of the latches 30 and thereby yieldably urge the latches in the contracting direction so as to clamp on the mentioned receptacle portion in such a way that the plug portion and receptacle portion will pull apart if a relatively strong pull is exerted on the cord or cable 43 while the receptacle portion 6 is held, which would otherwise break the cord or cable 43. However, in ordinary service, the latches 30 will securely hold the plug portion and the receptacle portion together and they may be rotated relative to each other while so connected. It will be observed that in the normal position of the parts described the foot portion 33 of the latches is above and slightly radially outward of the curved portion 38 on the interior of the skirt of the releasing collar 35.

When the releasing collar 35 is grasped and moved in a direction to compress the spring 40 while the plug and receptacle portions are connected, the rounded part 38 of the skirt of the releasing collar will ride against the outer end of the foot 33 and spread the latches 30 and at the same time the lower end of the skirt will be disengaged from the upper side of the long arm 31 of the latches and permit the latches to spread sufficiently to disengage from the receptacle portion. The movement of the releasing collar in the direction indicated will cause the rounded part 38 to have a cam action on the foot 33 of the latches which spreads the latches and unhooks the hook portions 32 of the latches from the receptacle portion, so that the plug portion and the receptacle portion may be separated simply by moving them in opposite axial directions. The plug portion 7 may be assembled or connected to the receptacle portion 6 simply by roughly axially alining the plug portion and the receptacle portion and pushing them together. It will be noticed that as the latches 30 are engaged with and are spread by the beveled portion 11 on the receptacle portion in the act of pushing the plug portion into engagement with the receptacle portion, the frustro-conical part 26 of the plug portion advances into the receptacle portion ahead of the rest of the plug portion. This produces early engagement of the contact 51 of the rod 46 with the upper head of the contact 22.

The cable or cord 43 passes through the cap 42 which is threaded on the upper end of the body 25 as indicated at 44, and the wires in the cable or cord 43 pass through accommodating openings in the body 25, and one of the wires is connected to an L-shaped connection 45 located inferiorly of the body 25 and having an opening through which slides an axially arranged contact pin 46 which passes through the lower end of the body 25 and through a bushing 47 whose lower end is frustro-conical or tapered as indicated at

48 to enter the member 19 in concentrically spaced manner. A helical spring 49 is located in an accommodating recess in the bushing 47 and works between the bottom of the recess in the bushing 47 and a cross member 50 connected to the pin 46 in such a way as to keep the pin 46 pressed downwardly to engage its contact head 51 with the upper contact of the conductive pin 22 which is located within the member 19, when the plug portion is connected with the receptacle portion. A conductor 52 traverses the body 25 and has one end connected to the contact cylinder 53 and its remaining end connected to one of the wires of the cable or cord 43. The contact member 53 surrounds and receives in the bushing 47 and is itself fitted in the receiving opening in the lower end of the body 25 and the member 53 has on its lower end and engaging the bottom of the body 25 the rounded annular contact ring 54 which is received in the cupped formation 17 of the contact member 14 in the receptacle portion 6 as shown in Figure 2, when the plug portion is connected to the receptacle. The member 19 provides adequate segregation of the various contacts.

Although I have shown and described herein a preferred embodiment of my invention, it is to be definitely understood that I do not desire to limit the application of the invention thereto, and any change or changes may be made in materials, and in the structure and arrangement of parts, within the spirit of the invention and the scope of the subjoined claims.

What is claimed is:—

1. A plug connector comprising two dielectric separable bodies, one of said bodies having an annular retaining portion, latches pivoted on one of said bodies and engageable with said annular retaining portion, a sleeve mounted for longitudinal movement on said one body, said sleeve being movable to an axial position to engage with a first portion of said latches in a manner to hold the latches engaged with said annular retaining portion, said sleeve being movable to an opposite axial position to engage with a second portion of said latches in a manner to hold said latches disengaged from said annular retaining portion so as to enable separation of said bodies, one of said bodies having a centralized stationary contact and the remaining body having an axial spring pressed contact engageable with said centralized stationary contact, first annular contact means on said remaining body and second annular contact means on said one body arranged to be in engaged positions while said bodies are connected together, and a dielectric tubular member spaced radially inwardly from the first and second annular contact means and surrounding said spring contact whereby said axial spring pressed contact is positively prevented from becoming engaged with either of said annular contact means at any time.

2. A plug connector comprising two dielectric separable bodies, one of said bodies having an annular retaining portion, latches pivoted on one of said bodies and engageable with said annular retaining portion, a sleeve mounted for longitudinal movement on said one body, said sleeve being movable to an axial position to engage with a first portion of said latches in a manner to hold the latches engaged with said annular retaining portion, said sleeve being movable to an opposite axial position to engage with a second portion of said latches in a manner to hold said latches disengaged from said annular retaining portion so

as to enable separation of said bodies, one of said bodies having an axial spring pressed contact, a centralized stationary contact on the remaining body with which said spring pressed contact is engageable, first annular contact means on said one body and second annular contact means on said remaining body arranged to be in engaged positions while said bodies are connected together, and means spring pressing said second annular contact means toward said first annular contact means.

3. A plug connector comprising two dielectric separable bodies, one of said bodies having an annular retaining portion, latches pivoted on one of said bodies and engageable with said annular retaining portion, a sleeve mounted for longitudinal movement on said one body, said sleeve being movable to an axial position in engagement with a first portion of said latches in a manner to hold the latches engaged with said annular retaining portion, said sleeve being movable to an opposite axial position in engagement with a second por-

tion of said latches in a manner to hold said latches disengaged from said annular retaining portion so as to enable separation of said bodies, one of said bodies having an axial spring pressed contact, a centralized stationary contact on the remaining body with which said spring pressed contact is engageable, first annular contact means on said one body and second annular contact means on said remaining body arranged to be in engaged positions while said bodies are connected together, means spring pressing said second annular contact means toward said first annular contact means, and a dielectric tubular member surrounding and projecting axially from said centralized stationary contact and spaced radially inwardly from said first and second annular contact means whereby said axial spring-pressed contact is positively prevented from becoming engaged with either of said first and second annular contact means at any time. 20
